RAIL CROSSING

Paul Speer, La Grange, Ill., assignor to Speer Filler Strip Company, La Grange, Ill., a corporation of Illinois

Filed Sept. 11, 1953, Ser. No. 379,676

7 Claims. (Cl. 238—8)

This invention relates to a new and improved rail crossing. In one of its aspects this invention relates to a rail crossing particularly adapted to allow vehicles with small diameter wheels to cross tracks at right angles without shock or damage to the wheel or vehicle. In another of its aspects this invention relates to an elastic resilient strip, particularly adapted to be placed between a railroad crossing bed and the rail, having a particular cross section and resiliency.

Anyone who has ever pulled a coaster wagon or pushed a baby carriage across a railroad crossing can appreciate the jolting and shock experienced by the vehicle and its contents. While this may seem academic at first the problem becomes extremely acute, especially in large industrial plants where material is transported to various parts of the plant in small-wheeled vehicles pulled by battery-driven tractors in long trains, as for example, in large packing plants where hams and other meats are transported from the cutting room to the curing and smoking rooms. The trucks or carts so employed are usually provided with wheels having a small diameter, for example, 12 to 18 inches. Some have small solid rubber tires; others do not. The damage to the wheels of the carts or trucks even over short periods of continued crossing of railroad tracks is quite extensive and amounts to a considerable item of expense for maintenance of the trucks or carts. I have now provided an improved rail crossing whereby vehicles having small-diameter wheels can cross in comfort without shock or damage to the wheel or vehicle.

It is therefore, an object of this invention to provide a new and improved rail crossing.

Another object of this invention is to provide a smooth crossing surface to allow vehicles with small-diameter wheels to cross the railroad tracks at right angles without shock or damage to the wheel or vehicle.

A further object of this invention is to provide a smooth surface for crossing railroad tracks in an industrial plant or buildings where it is necessary to have railroad tracks in concrete surfaces or industrial floors.

Still another object of this invention is to provide a smooth surface in industrial floors or industrial working areas where tracks are used to move large doors or machinery employing flanged wheels requiring a groove in the surface to accommodate the flange.

Yet another object of this invention is to provide a resilient material adapted to be placed between a railroad crossing bed and the rail.

Another object of this invention is to provide a means of securing a synthetic rubber material to a pre-manufactured crossing bed to fill in the space between the crossing bed and the rail normally left open for the travel of the railroad wheel flange, thus providing a smooth surface for vehicles traveling across railroad tracks at right angles.

Further and additional objects of this invention will become apparent upon reading of the disclosure and claims.

2

Figure 1 is a sectional view showing a preferred embodiment of my improved railroad crossing.

Figure 2 is an enlarged sectional view showing the disposition of the resilient strip in the narrow space and also showing a wheel crossing the rail transversely.

Figure 3 is an enlarged sectional view showing the compression of the resilient strip by the flange of the railroad wheel.

Figure 4 is a longitudinal sectional view taken along the line 4—4 of Figure 3.

According to the present invention a smooth transverse crossing surface of a rail or rails is accomplished by filling in that space normally left open for the travel of the wheel flange with a strip of resilient material of a certain shape and resiliency. The shape of the resilient strip is such as to provide a space for displacement caused by the downward force due to the weight of the wheel flange, yet by design is sufficiently rigid to support the lesser weights of vehicles crossing at right angles to the rail and strip. Besides effecting a smooth crossing several other important advantages are realized by the present invention. For example, by using a rubber filler strip it is possible to allow for expansion and contraction of the crossing bed without damage to the crossing during extreme heat or cold and such shape and resiliency prevents damage to the crossing or interference with the operation of the flanged wheel due to ice formations or the accumulation of solid matter in the normally void space between the rail and crossing bed. Also, it is advantageous to employ a strip made of a synthetic rubber or elastic material which is resistant to oil and other chemicals normally found or which accumulate in a plant, and which may deteriorate or corrode other non-resistant elastic materials. Of course, it will be appreciated that my invention has extremely wide application, not only in industrial plants where small-wheeled vehicles must cross transversely to rails, but also at many railroad crossings for motor cars and trucks. Indeed, many motorists would be extremely grateful for a smooth railroad crossing.

Referring now to Figure 1 of the drawing in particular, illustrated is a preferred modification of my improved rail crossing. Shown is a pair of rails 10 suitably secured to tie 11 by conventional means, not shown, viz., a rail spike. Disposed between the rails are a pair of pre-manufactured concrete slabs 12 forming the crossing bed, the surface of which is level with the top of the rails 10. These slabs are constructed of channel iron 13 and concrete 14, and are usually pre-manufactured in lengths of from 4 to 6 feet, width of about 2 feet and a thickness of about 4 inches. These slabs are supported upon a series of furring strips 15, only one of which is shown, which are disposed upon the individual ties 11 and act as a shim to bring the surface of the slabs to a height equal to the top of the rails. The slabs and furring strips are secured to the ties by means of bolts 25, Figure 4. Railroad regulations, in general, require that a space of 3 inches be left to allow for the flange of the railroad wheel to pass without obstruction. Disposed lengthwise in these narrow spaces is a pair of resilient elongated synthetic rubber strips 16 in the general shape of an inverted U. These rubber strips extend across the road and are preferably chamfered on each end to allow for a smoother encounter of the flange of the wheel with the rubber and less damage thereto than if a square corner was encountered. The strip completely fills the narrow space and is substantially flush at its upper exposed surface with the top of the rail and the crossing bed 12. It is preferred that the side of the strip in contact with the rail is slightly elevated, about $\frac{1}{4}$ to $\frac{1}{2}$ of an inch, and rounded to provide a slight tangential contact for the

wheel when it is on the top of the rail and coming toward the elastic strip, and also to provide a resilient body to fill a space which may be formed by wearing of the inside of the rail by the flange of the wheel. On the outer sides of rails 10 and forming a part of the road are wood planks 17, the surfaces of which are level with the rails and road. A small space 18 is provided to allow for expansion.

Referring to Figure 2, the strip 16 is held securely within the narrow space by means of steel plate 20 which is tack welded 21 to channel iron 13. A plurality of bolts 22 at spaced intervals are attached to plate 20, as for example by welding, and extend through one leg of the U portion of the rubber strip which is held securely by nuts 26 and washers 27. Before putting the rubber strip into place one side can be coated with a suitable rubber cement to provide an adhesive bond between the rubber strip 16 and plate 20. The rubber strip 16 is supported from below by means of a steel plate 24 which extends lengthwise with the rubber strip and which itself is supported by means of furring strips 15 and ties 11.

I prefer to employ a synthetic rubber strip in the general shape of an inverted U. This shape adapts itself readily to compression by the flange of the wheel as it passes over the top of the rubber strip. Figure 3 illustrates approximately what happens to the rubber strip as the flange of the wheel passes over it. It will be readily appreciated that the rubber strip may be in any other suitable form which adapts it to compression or displacement by the flange of the wheel, as for example, having a cavity in the center, rather than as a U. However, when the strip is of such nature the problem of securing it firmly within the narrow space becomes more difficult.

Resiliency is another characteristic of the strip which must be taken into consideration. Resiliency is usually determined in terms of durometer value, which is analogous to the hardness of metals. It is graded from soft to hard with the numbers ascending to the hard range. Pure gumstock rubber has a durometer resiliency of about 30 and hard rubber has a durometer resiliency of about 100. The resiliency of the rubber strip employed according to the present invention can vary, depending upon several factors, such as the general climate or climatic conditions under which the crossing is to be subjected, and the type of vehicles which cross over the crossing. In general, the resiliency can vary between 45 and 60 durometer. I prefer, in the case of crossings to be employed in industrial plants which small-wheeled vehicles pass over, to use a synthetic rubber strip having a resiliency of from 55 to 60 durometer.

The resilient strip can be fabricated out of any one of a number of rubber or rubber-like materials. I prefer to employ a synthetic rubber which is oil-resistant and corrosion-resistant and which adapts itself very well to use in industrial plants where there is spillage or accumulation of material which might corrode the rubber strip or deteriorate it. My preferred material is polychloroprene rubber, commonly known by the trade name Neoprene. However, other synthetic oil-resistant elastomers such as fluorocarbon and silicone rubbers and polyethylene and Buna type rubbers to some extent can also be employed. Also, natural rubber and synthetics such as polybutadiene, polyisoprene and GR-S rubber can be employed where the requirement of oil resistance is not imperative. In general, the type of material of which the resilient strip is fabricated can be chosen depending upon the traffic and conditions to which the rail crossing is to be subjected.

Referring again to the drawing, Figure 4 is a longitudinal view taken along the line 4-4 of Figure 3, illustrating partly in section the compression of strip 16 by the wheel flange. Occasionally the rubber strip may become stuck under the rail. This can be remedied by putting a thin coating of grease on the inner side of the

strip contacting the rail. Also shown is the spacing of bolts 22 which helps to hold strip 16 securely in place. Shown also is the longitudinal extension of supporting plate 24 as supported by furring strips 15 and ties 11. Also shown is one of the bolts 25 which secures prefabricated slabs 12 and furring strips 15 to ties 11. It will be noted that the head of bolt 25 is countersunk so that its upper surface is level with the top of the slab.

While this invention has been described and exemplified in terms of a preferred modification, those skilled in the art will appreciate that many changes can be made without departing from the spirit or the scope of the invention. For example, instead of using prefabricated concrete slabs as the crossing bed it is possible to use such things as guide rails and/or planks, or asphalt or other surfacing material. Also, the resilient strip may be secured within the narrow space by other means than those disclosed and may be supported from below by other means than those shown, all of which would readily suggest themselves to one skilled in the art.

I claim:

1. An improved rail crossing comprising, in combination, a pair of rails providing a guide for flanged railroad wheels; a crossing bed disposed between said rails and defining two parallel elongated narrow spaces through which the wheel flanges pass, the upper surface of said crossing bed being substantially in the same plane as the tops of the rails; two elongated rubber strips in the general shape of an inverted U, having a resiliency of 45 to 60 durometer, each strip being disposed lengthwise in one of said narrow spaces, each conforming at its upper exposed surface with the shape of the narrow space, one side of each of the strips being elevated about $\frac{1}{4}$ to $\frac{1}{2}$ inch above the top of the rail at the juncture with the rail, the other side being substantially flush with the crossing bed; and means for securing each resilient strip to said crossing bed.

2. A rail crossing according to claim 1, wherein the means for securing each resilient strip to said crossing bed comprises a steel strip disposed lengthwise in said space between said crossing bed and said resilient strip and fixedly secured to said crossing bed, and a plurality of bolts, each fixedly secured to said plate at intervals and extending through the adjacent leg portion of said resilient strip.

3. An improved rail crossing comprising, in combination, a rail providing a guide for a flanged wheel, a side wall disposed parallel to said rail, a bottom wall forming with said side wall and said rail an elongated narrow space into which the wheel flange passes, the top of said side wall being substantially in the same plane as the top of the rail, an elongated rubber strip disposed lengthwise in said narrow space conforming at its upper exposed surface with the shape of said narrow space, said upper surface of said strip being substantially flush with the tops of said rail and said side wall, said strip being in the general shape of an inverted U with the legs thereof resting on said bottom wall, and means for firmly securing to said side wall the leg of said strip which is adjacent said side wall.

4. A rail crossing structure according to claim 3 wherein said securing means includes a bolt extending from said side wall through one leg of said inverted U-shaped strip, and a nut disposed between the legs of said inverted U-shaped strip and engaging the end of said bolt to bind said leg through which it extends tightly to said side wall.

5. An improved rail crossing comprising, in combination, a rail providing a guide for the flanged wheel of a railway car, a side wall disposed parallel with said rail and having its top substantially as high as the top of said rail, a bottom wall forming with said side wall and said rail an elongated narrow space into which the wheel flange passes, an elongated elastic resilient strip disposed lengthwise in said narrow space resting on said

bottom wall and generally conforming at its upper exposed surface with the shape of said narrow space, the side of said strip adjacent said rail being elevated slightly above the top of the rail, the cross section of said strip being smaller in area than the cross section of said narrow space so as to provide a cavity into which the resilient material of said strip may flow when deformed by the passing of a railway car wheel, said strip being capable of supporting the wheels of vehicles passing over it transversely to the rail to thus smooth the passage of cross traffic while being yieldable to permit passage of a flanged railway car wheel longitudinally along the rail without lifting the wheel from the rail.

6. A rail crossing structure according to claim 5 where-
in said strip has a leg portion resting at its lower end
on said bottom wall and disposed adjacent said rail
directly beneath the path of the flange of a railway car
wheel as the wheel passes along the rail, said leg portion
being adapted to provide support to cross traffic but
being resiliently deformable to permit depression of the
top surface of the strip to receive the flange of the rail-
way car wheel as it passes thereover.

7. A rail crossing structure according to claim 5 where-
in said strip has a resiliency of about 45 to 60 durometer.
